UNITED STATES PATENT OFFICE.

WILLIAM B. RUGGLES, OF BAYONNE, NEW JERSEY.

PORTABLE DRIER.

1,171,144.

Specification of Letters Patent.

Patented Feb. 8, 1916.

Application filed December 16, 1910. Serial No. 597,610.

To all whom it may concern:

Be it known that I, WILLIAM BARKER RUGGLES, a citizen of the United States, residing at Bayonne, in the county of Hudson and State of New Jersey, have invented certain new and useful Improvements in Portable Driers, of which the following is a full, clear, and exact description, such as will enable others skilled in the art to which it appertains to make and use the same.

This invention relates to driers, and with respect to its more specific features, to portable driers of the kind involving a substantially horizontal rotating drum through which a heating medium is adapted to flow,

One of the objects of the invention is to provide a drier of the above type of such substantial construction that it may be readily and easily transferred from place to place without impairing its efficiency.

Another object of the invention is the provision of a drier of the above style with a liquid fuel heating system which not only efficiently dries the material, but is readily adapted to the necessities of transportation.

Another object of the invention is the provision of a simple and efficient furnace, preferably of the oil-burning type, and one which is especially desirable in connection with a drier of a portable character.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

40 In the accompanying drawings wherein are illustrated some of the various possible embodiments of the invention, Figure 1 is a side elevation of the portable drier; Fig. 2 is a plan view; Fig. 3 is a front end elevation; Figs. 4 and 5 are detail views of the feeding buckets; Fig. 6 is an enlarged longitudinal sectional elevation of the discharge end of the drier. Fig. 7 is a front elevation of the feed end of the drier.

50 The numeral 1 indicates a support or wagon body beneath which are suitably attached running wheels. The support may be of any suitable material and construction, but is preferably of a generally rectangular shape, comprising metallic I-beams suitably

spaced and braced to provide a substantial framework to support the several devices composing the drier. The rear running wheels are so joined to the support as to be capable of steering the same. Mounted on 60 cross-pieces of the support are two series of bearing rollers 2, made of chilled iron. These rollers are arranged in line across the support and suitably placed to accommodate the curvature of the drier drum.

65 The drier comprises two concentrically arranged shells 3 and 4 of generally cylindrical shape. The outer shell 3 is provided exteriorly with two heavy rolled steel tires 5 riveted thereto, which, when the drum is mounted on the support, rest on the rollers 2, said rollers being so placed at either end of the support as to maintain the drum slightly inclined to the horizontal when the support is in normal level position. Thrust bearing rollers 5' are provided to prevent longitudinal movement of the drum. The shell 3 is also provided exteriorly with a gear 6 concentric therewith, meshing with a pinion 7 on a shaft having a bevel gear 8 70 engaging a bevel gear 9, rotatable on a cross shaft 10, carrying at one end a sprocket wheel 11, and at its other end belt wheels 12 and 13.

75 The outer shell of the drier drum is made 85 of steel plates. The inner shell or flue 4 is also made of steel plates and is connected to the outer shell by cast iron straps 21, solidly riveted to both cylinders so as to hold the two shells rigidly together. Between the center and each end are sets of 90 flexible links 24, which allow for expansion and contraction due to changes in temperature. The drum is also provided with longitudinally disposed vanes 24' arranged about its inner wall to lift and stir up the material as it passes along.

95 The inner shell or flue 4 is enlarged as at 14 near the head or feed end of the drum and extends beyond the outer shell, passing 100 through the stationary head or hood 15 and surrounding, but spaced from a combustion chamber or flue 16, in which combustion of fuel for heating takes place. The fuel burner will be described hereinafter. The chamber or flue 16 is concentrically and 105 adjustably supported with respect to the enlarged portion 14 of the flue by means of the straps 17 and 18 and the ring 19 (see Fig. 3), its end extending beyond the flue 4 and 110

the hood. The ring and straps hold the chamber 16 loosely and its position may therefore be adjusted with respect to the flue 14. As shown, the straps 17 are secured 5 to a generally rectangular framework consisting of angle bars 20 and brace bars, while the straps 18 are secured to the cap 22 of the hood. The outer end of the chamber 16 may be open its full diameter, but preferably a head 23 is provided, having a central 10 opening leading into said chamber.

The chamber or flue 16 is preferably lined 15 with fire brick, and projects into the enlarged end 14 of the flue 4, and provides a concentric opening or space between the outer face of the one and the inner face of the other communicating with the atmosphere and the flue 4 for the free entry of fresh air to the flue 4 at this point. It will 20 be noted that the air passing through the space between the chamber 16 and enlarged portion 14 in the ordinary operation of the device will be heated by the walls of the chamber 16 and this heated air will enter 25 the flue at a point remote from the burner. The flue 4 passes through the greater portion of the length of the drum and opens directly thereinto at its rear end. By this construction it will be observed that when 30 a draft is established through the hood the products of combustion pass from the chamber 16, adjacent the front end of the drum, and are discharged to the rear through the flue 4, and back to the front end through the 35 space between the flue 4 and the outer shell 3.

The stationery hood 15 is of a generally cylindrical form closed at each end. The hood is supported by legs 25, which are attached to the body portion 1, and is further 40 held in place by plates 26 attached to the cap 22 and to the angle bars 20. The rear end of the hood is provided with a central opening adapted to receive and form a collar around the drum. Thus between the extension 45 14 and the periphery of the hood 15 an annular chamber is formed into which the drum opens.

In the upper portion of the hood is an opening communicating with a pipe 27 leading 50 to a stack or a rotary exhaust fan 28, which in turn communicates with the atmosphere. The fan and piping rest on a framework composed of angle bars 20 and 29 and braces 30. The shaft of the fan is provided 55 with a belt wheel 31 driven from the wheel 13 on the shaft 10. The hood is provided with doors 31' on opposite sides of the center to permit entry thereto and to the drum. The farther end of the drum is provided 60 with a door for a similar purpose. The material to be dried is introduced into the drum through an inclined spout 32 situated at the head of the drum between the shell 3 and the flue 14. The delivery end of the spout 65 terminates above the center of the drum and

the material falls upon a series of shovels or buckets to feed or guide the material well into the drum.

In the preferred form of feed device shown in Figs. 4 and 5, the material is 70 caught and deflected into the drum by a circular series of members, herein shown as flat plates or buckets 33. These plates are formed of integral pieces of steel and are preferably attached in any convenient manner to the inner periphery of the drum 3 and the outer periphery of the flue 14. The plates are preferably quadrilateral and have two parallel straight edges and two curved edges, the curved edges being adapted to 75 conform respectively to the outer periphery of the flue 14 and the inner periphery of the drum 3. Each plate, as shown in this embodiment, lies in a plane perpendicular to the surface of the inner flue and oblique to 80 its axis and each one is inclined inwardly downward, its plane hence being oblique to the periphery. On account of the general structure and disposition of the plates, the material delivered upon them is urged well 85 into the drum when the latter is rotated. Such buckets could also be used, of course, with a non-rotating drum. The bucket structure may be easily and cheaply made and on account of its simplicity and composition is very durable.

The material may be fed to the spout in any approved way, but in order to make the drier automatic, a conveyer of suitable character is provided. In the present instance, an endless conveyer or elevator 34 is 90 removably supported at one end by the framework of angle bars 20. The buckets of the conveyer deliver into the spout 32. The upper shaft 35 of the conveyer turns in 95 suitable bearings on the angle iron framework and is provided with a bevel gear 36 meshing with a similar gear 37 attached to a shaft 38 suitably supported. To the shaft 38 is fixed a sprocket wheel 39 and a 100 sprocket chain connects the wheel 39 with the sprocket wheel 11 on the shaft 10.

The discharge end of the drum is provided 105 with a central opening and around said opening on the inside of the end of the drum and oblique to the edge thereof are secured a plurality of flights or plates 40, Z-shaped 110 in cross-section. These plates with the end plate of the drum form pockets which are open at each end, and as the drum revolves 115 the dried material at the end of the drum is scooped up by the outer open end of the pockets and as the pockets incline the material is discharged from their inner open ends. The rear end of the drum is also 120 provided with a central opening 41, and mounted opposite the opening within the drum is a discharge plate 42 of conical formation having a plurality of radially disposed partitions 43. The apex of the cone 125 130

projects centrally through the opening 41 and the curved surface spans the depth of the Z-shaped plates. By this construction the dried material in the bottom of the drum is raised above the opening as the drum rotates and is delivered from the pockets 40 upon the curved surface of the cone, which deflects it through the opening. The partitions 43 are intended to prevent any material falling back into the drum.

The heat used in the drier is derived from the combustion of liquid fuel, preferably some oil like "fuel oil." The support 1 carries a liquid fuel burner 59 and a fuel and air supply system. This system comprises a fuel tank 60 and an air pump 61 operated by a belt from the wheel 69 on the shaft 10. A pipe 62 extends from the pump to the tank and serves to deliver air therein to force the fuel oil from the tank up through the pipe 63 to the burner which is situated in juxtaposition to and adapted to deliver into the chamber 16. Pipe 62 is held in place by braces 64 extending from the frame 1 and pipe 63 is secured to the angle bars 20. Another pipe 65 extends from pipe 62 to the burner and is adapted to supply air to the burner. This pipe is likewise supported by the bars 20. All pipes are provided with regulating valves and the burner is provided with the customary needle valve. The oil fed to the burner from the tank is sprayed by the air at the needle valve into the flue or chamber 16. Ignition of the mixture results in a large volume of highly heated products which pass into the extension 14 of the flue 4.

As driers of the type herein described are of somewhat large proportions and considerable weight, their practicability is added to by any reduction of their size, or the weight of parts, without sacrificing strength or capacity. By employing an oil burner of the kind herein described an efficient drier of comparatively small size and weight is produced, and one which is portable and easily manipulated. Suitable brake shoes 66 for the wheels are provided and may be operated through the hand lever 67 and the rod 68.

The operation of the drier is as follows: The drier is connected by a belt on the pulley 12 to any suitable source of power. Through the described gearing the drum is rotated, the fan is operated, and the pump set in motion to feed the oil and air to the burner 59. The combustible mixture in the chamber 16 is ignited, and the products of combustion pass therefrom into the flue 4, drawing into the flue 4 a further supply of air, by injector action, through the opening between the flues 4 and 14, for the consumption of any incompletely burned products in the flue 4. The hot and partly burning

gases heat the material in the drier as they

pass from one end to the other through the flue 4, and they emerge into the drum at the farther end. From here the gases pass back to the head of the drum in contact with the material to be dried, thence into the hood, 70 whence to the fan or into the stack, according to which is employed. The conveyer feeds the material into the spout, whence it passes into the drum by way of the buckets, the rotation of the drum continually turning the 75 material over and over and dropping it onto the hot flue 4, whence it falls to the bottom of the drum, the inclination of the drum causing the material to progress from end to end therein. The Z-shaped 80 plates or buckets raise the dried material and deliver the same onto the conical deflector which discharges it from the drum.

As many changes could be made in the above construction and many apparently 85 widely different embodiments of this invention could be made without departing from the scope thereof, it is intended that all matter contained in the above description or shown in the accompanying drawings shall 90 be interpreted as illustrative and not in a limiting sense.

It is also to be understood that the language used in the following claims is intended to cover all of the generic and specific 95 features of the invention herein described and all statements of the scope of the invention, which, as a matter of language, might be said to fall therebetween.

Having described my invention, what I 100 claim as new and desire to secure by Letters Patent is:—

1. In an apparatus of the character described, in combination, a movable support, a rotatable drier thereon, a rotatable flue, a 105 combustion chamber embraced by said flue, and a fluid fuel burner projecting into said combustion chamber.

2. In an apparatus of the character described, in combination, a movable support, a rotatable drier thereon, a rotatable flue 110 therein adapted to convey heat to said drier, a combustion chamber relatively fixed with respect to the rotative motion of said flue and embraced thereby, said chamber being 115 adapted to deliver products of combustion to said flue, and a fluid fuel burner projecting into said chamber.

3. In an apparatus of the character described, in combination, a movable support, a rotatable drier thereon, a hood about one 120 end of said drier and forming an exit for gases emerging therefrom, a flue held in said drier and having a portion projecting therefrom and through said hood, a combustion chamber embraced by said flue and projecting thereinto to a point adjacent said end of the drier, and a fluid fuel burner projecting into said chamber.

4. In an apparatus of the character de-

- scribed, in combination, a movable support, a rotatable drier drum thereon, a flue held in said drum and rotatable therewith, a hood surrounding one end of said drum, said flue projecting through said hood, a combustion chamber positioned within the projection of said flue and spaced therefrom, and a fluid fuel burner projecting into said combustion chamber.
- 10 5. In an apparatus of the character described, in combination, a movable support, a rotatable drier drum thereon, a flue held in said drum and rotatable therewith, a hood surrounding the end of said drum adapted to receive products of combustion emerging therefrom, said flue projecting through said hood to a point exterior thereof, a combustion chamber adjustably held within the end of said flue, and a fluid fuel burner projecting into said combustion chamber.
- 15 6. In an apparatus of the character described, in combination, a movable support, a rotatable drum carried thereby, a conveyer attached to said support and adapted to feed the drum, a fluid fuel burner mounted on the support and adapted to deliver its product to the drum, means for establishing a draft from said burner into and through the drum, and means carried by the support to simultaneously operate the drum, the conveyer and the draft establishing means.
- 20 7. In an apparatus of the character described, in combination, a movable support, a rotatable drum carried thereby, a fluid fuel burner mounted on the support and adapted to deliver its product to the drum, and means adapted to establish a draft in said drum and mounted on said support comprising a fan communicating with an outlet outside said drum, and means mounted on said support adapted to operate said fan.
- 25 8. In an apparatus of the character described, in combination, a support, a fluid fuel burner supported thereby, a drier drum supported thereon, a hood adapted to receive the end of said drum, a discharge flue surrounded by said hood, and a combustion chamber surrounded by and spaced from said discharge flue and supported adjacent said hood, said combustion chamber being adapted to receive products of combustion from said burner.
- 30 9. In an apparatus of the character described, in combination, a movable support, a fluid fuel burner supported thereby, a drier drum supported thereon, a hood mounted on said support and adapted to receive the end of said drum, a discharge flue extending into said drum and surrounded by said hood, and a combustion chamber concentric with and spaced from said flue and adjustably supported relative to said hood, said combustion chamber being adapted to receive products of combustion from said burner.
- 35 10. In an apparatus of the character described, in combination, a movable support, a drier drum carried thereby, a hood adapted to receive the end of said drum, a discharge flue surrounded by said hood, a combustion chamber surrounded by said flue, spaced therefrom, adapted to deliver products of combustion thereto, and a fluid fuel burner adapted to discharge into said combustion chamber.
- 40 11. In an apparatus of the character described, in combination, a rotatable drum having a feed opening, a flue surrounded by said drum, and a member attached to said drum and said flue adapted to deflect material into said drum.
- 45 12. In an apparatus of the character described, in combination, a rotatable drum open at one end, a flue surrounded by said drum, and flat plates secured to said flue and to said drum and adapted to deliver material therein.
- 50 13. In an apparatus of the character described, in combination, a rotatable drum having a feed opening in its head, a flue extending within said drum having an enlarged portion, and quadrilateral flat plates obliquely secured to the inner periphery of said drum adjacent said opening and attached to said enlarged portion, said plates being perpendicular to said flue and inclined to the axis thereof.
- 55 14. In an apparatus of the character described, in combination, a movable support, a fluid fuel burner carried thereby, a rotatable drum having a flue mounted on the support, means provided for the introduction of the products of combustion from said burner into said flue, and means adapted to inject air into said flue at a point remote from said burner.
- 60 15. In an apparatus of the character described, in combination, a movable support, a hood on said support having an opening for the exit of products of combustion, means adapted to establish a draft through said opening, a drum on said support communicating with said hood, a combustion chamber, a fluid fuel burner adapted to discharge into said combustion chamber, means adapted to guide products of combustion from said combustion chamber to said opening comprising a flue in said drum and communicating with said combustion chamber, and means adapted to prevent the passage of products of combustion from said combustion chamber to said opening under the influence of said draft except by way of said flue.
- 65 16. In an apparatus of the character described, in combination, a movable support, a hood on said support having an opening for the exit of products of combustion, means adapted to establish a draft through said opening, a drum on said support communicating with said combustion chamber, and means adapted to prevent the passage of products of combustion from said combustion chamber to said opening under the influence of said draft except by way of said flue.

cating with said hood, a combustion chamber, a fluid fuel burner adapted to discharge into said combustion chamber, means adapted to guide products of combustion from said combustion chamber to said opening comprising a flue in said drum and communicating with said combustion chamber, means adapted to prevent the passage of products of combustion from said combustion chamber to said opening under the influence of said draft except by way of said flue, a supply tank for fluid fuel, a pipe adapted to lead fuel to said burner, an air pump adapted to create a feed pressure in said tank, and a second pipe adapted to supply air to said burner and communicating with said pump.

17. In an apparatus of the character described, in combination, a movable support, 20 a hood on said support having an opening for the exit of products of combustion, means adapted to establish a draft through said opening, a rotatable drum on said sup-

port communicating with said hood, a combustion chamber, a fluid fuel burner adapted 25 to discharge into said combustion chamber, means adapted to guide products of combustion from said combustion chamber to said opening comprising a rotatable flue in said rotatable drum and communicating with said combustion chamber, means adapted to prevent the passage of products of combustion from said combustion chamber to said opening under the influence of said draft except by way of said flue, a supply tank for fluid 30 fuel, a pipe adapted to lead fuel to said burner, an air pump adapted to create feed pressure in said tank, and a second pipe adapted to supply air to said burner and communicating with said pump. 35

In testimony whereof I affix my signature, in the presence of two witnesses.

WILLIAM B. RUGGLES.
